PLASTIC NOVELTY ICE CREAM CONE

Perry Feuer, Roslyn, N.Y., assignor to Creative Creations, Inc., New York, N.Y.

Filed Nov. 25, 1970, Ser. No. 26,166

Term of patent 14 years

Int. Cl. D21—01

U.S. Cl. D34—15

FIG. 1 is a front perspective of a plastic novelty ice cream cone showing my new design;

FIG. 2 is a top perspective view of the design, and

FIG. 3 is the rear perspective view of the design shown in FIG. 1.

I claim:

The ornamental design for a plastic novelty ice cream cone, as shown.
